UNITED STATES PATENT OFFICE

WALTER E. INGHAM, OF NEW BRITAIN, CONNECTICUT, ASSIGNOR TO THE STANLEY WORKS, OF NEW BRITAIN, CONNECTICUT, A CORPORATION OF CONNECTICUT

DOOR HOLDER

Application filed March 27, 1929. Serial No. 350,207.

This invention relates to door holders adapted to be secured to the door and having a member adapted to engage the floor. It has been the practice to provide holders of this sort with floor engaging members in the form of fixed rubber tips or shoes in order that the holder may have a firm purchase on the floor. Door holders thus equipped, while giving general satisfaction, are open to numerous objections in certain applications as, for example, when applied to a door frequently used by persons who are in a hurry or who find it necessary to quickly push or shove the door open.

For example, in hospitals, doctors and attendants in passing out of doorways must, under the exigencies of certain cases, push the door violently in an attempt to further open it. When this is done, the fixed rubber tip, due to its purchase on the floor, does not permit the door to swing as easily as desired, and such movement as is given to the door results in the tip chattering and jumping, so to speak, along the floor. Further, the tip scratches and mars the floor. Of course, the holder could be tripped or released, but this would take time which is valuable in an emergency. At least half the number of times the door is used, the holder is on the wrong side.

The aim of the present invention is to provide an improved door holder wherein the above and other objections and disadvantages, incident to the use of door holders as heretofore made, are eliminated.

More particularly, an aim of the invention is to provide a very simple, effective and durable door holder with a rotatable, and preferably yielding, floor engaging member or roller which is resiliently forced down against the floor so as to have a purchase thereon, the roller being frictionally held against free rotation so as to offer the desired resistance to free swinging movement of the door, and the roller being adapted to roll over the floor when sufficient pressure is applied to the door without causing any undue inconvenience in the use of the door or causing chattering or noise and without marking

or marring the floor with which the roller is engaged.

My improved door holder is very durable and has a long life of usefulness as there is no appreciable wear between the floor engaging roller and its bearing or bearings, and the roller may be held with sufficient pressure against the floor to obtain the desired results without causing excess distortion and rapid wear of the roller. The device is characterized by its simplicity in construction and arrangement and its economy in manufacture, the parts being relatively few in number and being capable of cheap manufacture and ready assembly.

A further aim of the invention is to provide an improved door holder wherein the rotatable floor engaging member or roller is frictionally held against free rotation on its bearing or bearings without the use of springs (aside from the spring which urges the bolt downwardly), bolts or other equivalent means for urging the bearing surfaces into engagement or for adjusting the amount of friction or for taking up wear between the bearing surfaces, thus resulting in a more simplified and economical construction and avoiding any likelihood of the holder getting out of order.

Other objects will be in part obvious and in part pointed out more in detail hereinafter.

The invention accordingly consists in the features of construction, combination of elements and arrangement of parts which will be exemplified in the construction herein-after set forth and the scope of the application of which will be indicated in the appended claims.

In the accompanying drawings, wherein is shown one of the many embodiments which the present invention may take:

Figure 1 is a side view of the holder with parts in section, the door being shown diagrammatically in edge view and a portion of the floor with which the roller is engaged being shown in section;

Fig. 2 is a front view of the door holder;

Fig. 3 is a transverse sectional view through the roller; and

Fig. 4 is a perspective view of the roller and its bearings.

Referring to the drawings in detail, the holder is shown as having a casing formed of a base plate 10 and a face plate 11, the latter having a rectangular rib 12 which, together with the base plate, forms a hollow vertical barrel rectangular in cross section. Obviously, the casing may be of any suitable shape, 10 that shown in the drawings being illustrated by way of exemplification only. If desired, the barrel may be of circular or other form and, instead of standing out from the door, as illustrated, it may be located within the 15 compass of the door. The base plate has a slot 13 at the upper edge of which is an outwardly extending finger or wall 14. The numeral 15 designates a bolt corresponding in cross section to and slidably fitting within 20 the barrel 12. The bolt may be in the form of a hollow tube provided with a bottom end wall 16. In order to hold the bolt within the casing before the latter is attached to the door, there may be fixed to the bolt a spring 25 17 having its upper end turned outwardly so as to operate in the slot 13 and overhang the lower edge of that slot. Positioned within the barrel and the bolt, and between the walls 14 and 16, is a spring 18 for resiliently 30 holding the floor engaging roller in engagement with the floor while permitting the roller to accommodate itself to any unevenness or irregularities in the floor as it passes thereover. The lower end of the bolt is provided 35 with a pair of depending arms 20 provided with vertical slots 21 which extend to the lower ends of the arms. The numeral 22 designates a pin on which the floor engaging 40 element is rotatably mounted. This pin has its ends fitting in the slots 21 and, in order to prevent the pin from rotating, it has flattened faces 23, the diametrical distance between which is substantially equal to the 45 width of the slots 21.

In accordance with the present invention, 50 the device is provided with a roller having a floor engaging member 30 preferably formed of yielding material, such as rubber, and a hub or sleeve 31 preferably formed of metal. The hub may have, as illustrated, a circumferential groove in its outer periphery in 55 which the ring or floor engaging member 30 is seated, the periphery of the hub being preferably roughened so as to prevent slippage between the hub and the ring 30 or, if desired, the ring may be cemented on the hub or otherwise held thereon. The roller is rotatably supported on a pair of bearing members 32 mounted on the pin 22 at opposite 60 ends of the hub. The interengaging bearing surfaces between the hub 31 and the bearing members 32 are so disposed as to be inclined to the axis about which the roller turns. In the present illustrative disclosure, the ends 65 of the hub have conical or inclined bearing

surfaces 33, and the bearing portions 34 of the bearing members 32 are of complementary conical shape. The bearing surfaces are shown as disposed at an angle of 30° to the axis of the roller, but this may be varied 70 as desired. Thus, it will be seen that the opposed faces of the bearing members are oppositely inclined, and the hub is wedged upwardly between the bearing members when 75 the roller is forced against the floor. The bearing members 32 may, of course, be formed of any suitable material, but they are preferably formed of wood which may be impregnated with a lubricant in order to provide so-called oilless bearings. The outer 80 faces of the bearing members are flat and are adapted to abut against the inside surfaces of the respective arms 20. By preference, the bearing members have a more or less close fit upon the pin 22. The internal diameter of the hub 31 is considerably larger than the diameter of the pin 22 so as to allow a clearance therebetween and thus prevent engagement of the hub against the pin 85 in the event there should be wear between 90 the hub and the bearing members 32.

The operation of my improved door holder will be readily understood from the foregoing description taken in connection with the accompanying drawings. The door holder is secured to a door adjacent the free edge thereof, as shown in Fig. 1, the door being diagrammatically shown and being designated by the letter D. The spring 18 resiliently 95 forces the bolt 15 downwardly so as to press the cylindrical floor engaging member 30 against the floor which is designated by the letter F. The roller will flatten out somewhat, as illustrated in Fig. 1, the extent of flattening depending upon the resiliency or softness of the roller and the pressure with which the spring 18 forces the roller against the floor. This engagement of the roller 100 against the floor will offer some resistance to the free rotation and, thus, substantially free swinging movement of the door, but, if this factor of resistance were alone relied upon, it would be necessary to force the roller down against the floor under such undue 105 pressure as to result in rapid wear of the floor engaging member so that the arrangement would not be practical in actual use. The frictional engagement between the hub 31 and the bearing members 32 gives another 110 factor of resistance which obviates the necessity of forcing the roller with undue pressure against the floor. Due to the force with which the roller is urged against the floor, the hub 31 is pressed upwardly against the bearing 115 surfaces 34 and is more or less wedged therebetween so that there is that desired degree of friction between these bearing surfaces and the complementary surfaces of the hub added 120 to the resistance between the roller and the 125 130

floor to prevent free rotation of the roller, which means that the holder will maintain the door in any position of adjustment. In the practical embodiment of the invention disclosed in the accompanying drawings, the bearing members 32 are not positively fixed against rotation and, during the operation of swinging the door, these bearing members may turn with respect to the arms 20 of the bolt, it being apparent, however, that, due to the interengaging tapered surfaces between the bearing members and the roller, the bearing members are forced out and into frictional engagement with the inner or opposed surfaces of the arms 20. There may be some creeping or rotary movement between the bearing members and the roller and between the bearing members and the arms of the bolt, but, in any event, the opposed frictional surfaces are urged into frictional engagement with one another while the spring 18 is urging the roller against the floor so as to retard free rotation of the roller due to the fact that the surfaces between the bearing members and the roller are inclined at an angle to the axis of rotation of the roller. However, as the roller may, when sufficient force is applied to the door, turn upon its bearing, the door may move under sufficient pressure and, when one gives the door a push or shove in hurrying through the doorway, the door will move without unduly jarring or impeding the user.

It is important to observe that the frictional engagement between the hub 31 of the roller and the bearings 32, and between the bearings and the arms of the bolt, as the case may be, is partly instrumental in frictionally holding the roller against free rotation, and such frictional engagement is obtained without the use of springs or the like directly associated with the roller. There is practically no wear between the bearing surfaces so that the device will have a very long life and, in fact, will last as long as the normal life of a door. Such slight wear as may occur does not in any way effect the efficiency of the device.

It is evident that my improved device may have various embodiments without departing from the scope of the invention. If desired, the bearing members may be positively held against rotation, and the interengaging surfaces between the hub of the roller and the bearing members 32 may be other than of conical shape.

It is also to be understood that the language used in the following claims is intended to cover all of the generic and specific features of the invention herein described and all statements of the scope of the invention which, as a matter of language, might be said to fall therebetween.

I claim as my invention:

1. A door holder of the character described

having a roller adapted to engage the floor, bearing means on which said roller is journalled, said bearing means and roller having interengaging bearing surfaces disposed at an angle to the axis of rotation of the roller, and means for holding said roller against the floor.

2. A door holder of the character described having a roller adapted to engage the floor, means for rotatably supporting said roller and including bearing members with which said roller is in frictional engagement, said bearing members having their bearing surfaces so disposed that the distance between the bearing surfaces decreases in the direction in which the roller is urged thereagainst whereby said roller is wedged between said bearing surfaces when the roller is in engagement with the floor, and means for holding the roller against the floor.

3. A door holder of the character described having a roller adapted to engage the floor, means for supporting said roller and including a pair of bearing members having oppositely tapered bearing surfaces for said roller, and means for holding the roller against the floor.

4. A door holder of the character described having a roller provided with a yielding floor engaging portion, means for supporting said roller and including a pair of normally stationary bearing members having oppositely tapered bearing surfaces, said roller having at its opposite ends bearing surfaces tapered correspondingly to and adapted to engage the respective bearing surfaces of said bearing members, and means for holding the roller against the floor.

5. A door holder of the character described having a bolt, a pin non-rotatably carried thereby, bearing means carried by said pin, a roller journalled on said bearing means and adapted to engage the floor, and means pressing on said bolt for resiliently holding the roller against the floor, said bearing means and roller having interengaging bearing surfaces disposed at an angle to the axis of rotation of the roller.

6. A door holder of the character described having a roller provided with a yielding portion adapted to engage the floor, a bolt having a pair of opposed surfaces, a pin carried by said bolt and bridging the space between said surfaces, bearing members on said pin and between said surfaces and respectively engaging the latter, said bearing members having surfaces with which said roller is in engagement and which surfaces are so disposed that the distance between them decreases in the direction in which the roller is urged thereagainst, and a spring behind said bolt for urging said roller against the floor.

7. A door holder of the character described having a vertically movable bolt provided with a pair of opposed surfaces, a spring be-

hind said bolt, a pin carried by said bolt and bridging the space between said surfaces, a pair of opposed conical bearing members on said pin and respectively engaging said surfaces, and a roller about and engaging the conical portions of said bearing members and adapted to engage the floor.
